UNITED STATES PATENT OFFICE.

CARL PETERS, OF SHERBURN, MINNESOTA.

AUTOMATIC DOOR LATCH.

Application filed June 18, 1921. Serial No. 477,073.

To all whom it may concern:

Be it known that I, CARL PETERS, a citizen of the United States, residing at Sherburn, in the county of Martin and State of Minnesota, have invented certain new and useful Improvements in Automatic Door Latches; and I do hereby declare the following to be a full, clear, and exact description of the invention, such as will enable others skilled in the art to which it appertains to make and use the same.

This invention relates to a locking device, and particularly to such a device adapted to be applied to a door. While the invention is capable of many uses and applications, it is most especially intended for use on barn or stable doors, and such buildings where animals are kept. It is well known that cows and other animals often open locks on doors by rubbing against the door and engaging the lock with their horns.

It is an object of this invention therefore to provide a lock of simple construction so arranged that it is practically impossible for an animal to open the same by rubbing against the door or in a way to so engage the lock with her horn that the same will be opened.

It is a further object of the invention to provide such a lock which can be readily locked and unlocked from either the outside or inside of the door.

It is still another object of the invention to provide the portion of the lock on the outside of the door with a latch means adapted to engage a keeper to hold the door in open position.

These and other objects and advantages of the invention will be more fully set forth in the following description which is made in connection with the accompanying drawings, in which—

Fig. 1 is a view in side elevation of the lock and a portion of the door and door jamb to which it is applied, certain portions being shown in section;

Fig. 2 is a section taken substantially on the line 2—2 of Fig. 1; and

Fig. 3 is a view showing the latch holding the door in open position.

Referring to the drawings, a portion of the door *a* is shown which is adapted to close against the door jamb *b*. The door *a* is formed with an opening 1 extending therethrough and a keeper member 2 is applied to the inside of the door which has a U-

shaped portion 2^a projecting inwardly in alinement with the opening 1 and fastened to each side of the same. The keeper 2 also has a portion extending across the front of the door, as shown in Fig. 2, and is further bent to have a portion 2^b extending across the outside of the door, which portion is provided with an aperture 2^c in alinement with the aperture 1. The keeper is secured by the headed and nutted bolts 3 passing through the door and engaging the portion of the keeper at either side thereof. A handle and housing member 4 of suitable shape to form a convenient hand hold is secured to the outside of the door by the lower bolt 3 and another headed and nutted bolt 5 which passes through the same in its upper end.

The member 4 has a tapped hole in its lower curved portion and a pointed member 6 has a threaded shank screwed into said hole and projecting inwardly of said handle to form the pivot and supporting member for a bell crank lever 7 which is provided with a recess at the outer side of its angle portion, which recess is adapted to receive the pointed portion of member 6. It will be noted that the member 6 has a widened collar or shoulder portion adjacent the member 4 upon which the body portion of the lever 7 rests. The member 7 has one arm extending upwardly within the housing 4, which arm is bent at a slight angle toward the door at its upper end, and said member also has an arm extending through the aperture 1 which is of somewhat greater thickness than the vertical arm and extends nearly to the inside edge of the keeper 2. Normally, the horizontal arm of the member 7 will drop by gravity and the top edge of the vertical arm will rest against the inside of an opening 4^a formed in the top of member 4, in which opening the top edge of the vertical arm moves.

Secured to the jamb *b* is a housing or casing 8 comprising a plate bent into U-shape to form parallel side walls. Rivets or screws 9 extend between the walls of member 8 and the upper one of which is shown as forming the pivot member for a latch dog 10 which projects from casing 8 and is of hook formation and adapted to engage over the keeper 2. The front edge of the dog 10 is formed with an inclined surface 10^a forming a cam surface with which the edge of the keeper 2 is adapted to engage when the door is

moved inwardly. Rivets or screws 9^a also extend between the sides of the housing 8 and the upper of these is shown as forming a stop for the member 10. The member 10 is also provided with a projecting lip 10^b forming a handle therefor. It will be noted that the casing 8 and the latch member 10 are symmetrically formed, and by such formation are rendered capable of being reversed and inverted so that the casing and latch dog may be used with either a right hand or left hand arrangement of the door. When the members are so inverted, the members 9 and 9^a shown as the lower members in Fig. 1, will be used as the pivot and stop, respectively, for the member 10.

The member 4 is shown as having an upwardly projecting lip 4^b adjacent the opening 4^a, which lip is adapted to engage with a pivoted latch on the side of the building or member adjacent to which the door moves in its open position. Such a latch is shown in Fig. 3 as the member 11 provided with the opening 11^a, the same being pivoted for slight swinging motion to the plate 12 which will be suitably secured to the side of the building or other member 13. As the door a moves toward the member c the latch member 4^b will engage against the upwardly curved latch 11 and raise the same so that the member 4^b passes into the opening 11^a. The latch 11 will then drop by gravity and, if the door attempts to swing backwardly, it will be held by engagement of the latch 4^b with the latch 11.

The operation of the device will, doubtless, be obvious from the above description.

As the door swings toward the jamb, the upper edge of the keeper 2 will engage the surface 10^a and raise the latch 10 and as the door moves to closed position, the said latch will drop into the keeper and hold the same in closed position. Such position of the keeper is shown by dotted lines in Fig. 1. The normal position of the lever 7 is also shown in dotted lines in Fig. 1. When it is desired to open the door from the outside, the handle will be placed in the member 4 and the lever 7 moved toward the outer portion of said member. The lever will then be moved into the position shown in full lines in Fig. 1 and the horizontal arms of the lever will engage latch 10 and raise the same from the keeper.

If it is desired to lock or unlock the door from the inside, the same can be done by manipulating the latch 10 by the handle 10^b. By the arrangement of the keeper and latch it is obvious that it would be practically impossible for a cow or other animal to engage the latch with her horn, or otherwise, and open the latch or door. The pivot construction comprising the member 6 and the recess of lever 7 avoids any danger of the lock being frozen in cold weather, so that the lever

7 could not be moved. The manner in which the door will be held in open position has already been explained.

From the above description it is seen that applicant has provided a simple form of door latch, one which can be easily made and installed and which will have great utility for the purpose intended. The latch will preferably be made of suitable material, which, if desired, may be of non-corrosive character. The latch can also be made very strong and durable and is capable of application to either single, double, or sliding doors.

It will, of course, be understood that various changes may be made in the form, details and arrangement of the device without departing from the scope of applicant's invention, which, generally stated, consists in the matter shown and described and set forth in the following claims.

What is claimed is:

1. A latch device comprising a keeper adapted to be secured to the inside of a door, a latch pivoted to swing about a horizontal axis parallel to the door and adapted to be secured to the door jamb, and so arranged that it will be raised by the keeper and engage with the same, a housing handle member secured to the outside of the door, a lever mounted therein to swing on a horizontal axis parallel to the door having one arm adapted to extend through the door and engage the said latch to lift the same, and having another arm extending vertically in said handle portion normally spaced from the front thereof.

2. A lock for a door having in combination a keeper secured to the inside of said door, a latch dog pivoted to the door jamb on a horizontal axis parallel to the door and adapted to engage in said keeper, having a cam surface by which it is raised by movement of said keeper, a pivoted means on the outside of the door mounted to swing about a horizontal axis parallel to the door and extending therethrough adapted to engage with said dog to raise the same out of engagement with said keeper, and a handle member on said dog by which it can be operated from the inside of said door.

3. The structure set forth in claim 1, said housing handle member having an opening in its top portion in which the upper end of said lever moves, and an upwardly curved projection adjacent said opening adapted to engage a fixed keeper to hold the door in open position.

4. An automatic latch comprising a keeper adapted to be secured on the inside of the door, pivoted means adapted to be secured to the door jamb for engaging said keeper, a housing handle adapted to be secured to the outside of the door, and a lever loosely and removably pivoted in and enclosed by

said handle for operating said pivoted means.

5. The structure set forth in claim 4, said housing handle having a latch means projecting upwardly therefrom adapted to engage with a member to hold the door in open position.

6. A latching device for a door having in combination a keeper comprising a U-shaped portion extending from the inside of the door and extending around the edge of the door and across a portion of the front surface thereof, said keeper having an opening through the latter portion arranged in alignment with an opening in the door, a housing handle secured to the front of the door, a bell crank lever pivoted at the lower portion of said handle housing within the same, a pivoted latch secured to the door jamb and adapted to engage within said keeper, said lever having a substantially horizontal arm extending through the opening in the door to engage with said latch, and a vertical arm extending upwardly in said handle housing adapted to be moved to raise the said latch.

7. A latch structure comprising a keeper adapted to be secured to a door and projecting from the inner side thereof, a handle

member secured to the outside of the door constituting a curved housing, a lever detachably pivoted in the lower portion of said handle, said lever having a substantially horizontal arm extending through the door into said keeper and a substantially vertical arm centrally disposed laterally in said handle, adapted to be grasped with said handle and moved to raise the horizontal arm.

8. The structure set forth in claim 7, said handle having an opening in its upper portion into which the vertical arm extends and moves.

9. A latch structure comprising a curved handle secured at its top and bottom ends to the outside of a door, a pointed member secured to and projecting into said handle and a bell crank lever having a tapered recess therein supported and pivoted on said member, with said member disposed in said recess.

In testimony whereof I affix my signature in presence of two witnesses.

CARL PETERS.
